SMOKER'S PIPE CASE

Perry C. Farmer, Tacoma, Wash.

Application July 16, 1946, Serial No. 683,809

2 Claims. (Cl. 206—41)

1

This invention relates to carrying cases for smokers' pipes, and has for its objects to provide a case which will completely contain the pipe; which will allow the pipe to remain lighted a reasonable time while contained therein; which has no metal part in its construction; in which the elastic used to maintain it in closed position may be readily renewed; which is shaped so that when it is pulled from the pocket of the user, it will not catch on the pocket nor on any of the articles therein; which fits over and under the pipe bowl; which may be readily cleaned; which may be provided with a chain or cord to prevent its loss; which may be molded or carved; which may be made of wood or plastic; which, while enclosing the pipe, leaves a sufficient part of the bowl sides exposed to permit it to be firmly grasped by the fingers in inserting and removing the pipe from the case; which, while having a hinged action is not provided with any hinge; which is of strong construction, neat in appearance, durable in quality, inexpensive to make, and effectively fulfills its purpose.

I attain these and other objects by the devices and arrangements illustrated in the accompanying drawings, in which—

Fig. 1 is a plan of my improved pipe case; Fig. 2 is a vertical section of the upper part thereof; Fig. 3 is a similar view of the lower part thereof; Fig. 4 is a section taken on the line 4—4 in Fig. 2; and Fig. 5 is a side elevation thereof, showing the pipe in broken lines, and showing the position of the parts when the pipe is being inserted therein or removed therefrom, also in broken lines.

Similar numerals of reference refer to similar parts throughout the several views.

My invention is constructed of two separate and unattached parts, held together normally by an elastic means, and held in proper hinged relation to each other by separable interlocked parts.

The upper member 6 is provided with a head 1 which is preferably stream-lined in shape, as seen in Fig. 1 to prevent its entanglement with the user's pocket, or its contents, when it is being withdrawn therefrom; and with a stem 8 which is curved in section as seen in Fig. 4.

The under side of the head 1 is provided with a cavity, or inverted cup, 9 adapted to hold the top part of the pipe bowl, and having a flange, or lip, 10 forming such cavity. The head 1 is raised above the stem 8 to accommodate the shape of the particular pipe for which it is made.

The stem 8 is provided with an open groove 11

2

in its under side, adapted to receive the stem of the pipe. The stem 8 also has two shoulders 12, on the sides of the groove 11 (Fig. 4) adapted to receive the lower member 13 of the case. A depression 14 is made in the rear end of the stem 8 adapted to receive the holding lug 15 of the lower member 13 to act therewith as a hinge about which the said lower member 13 may be swung in inserting or removing the pipe.

10 A groove 16 extends around the outer surface of the stem 8 and is adapted to receive and hold the elastic ring 17, of rubber or other suitable material. A staple 18 is placed in the rear end of the stem 8 to hold a chain, or cord, 19 which may have a ring 20, or other means adapted to be slipped over a button in the clothing of the user, to retain the case in his possession, should he be of a forgetful nature.

The lower member 13 of the case comprises 20 a substantially flat piece 21 having a flanged head 22 adapted to fit the under surface of the pipe bowl. The part 21 is also provided with a groove 23, coordinated with the groove 16 of the stem 8, to receive the same rubber ring 17 which surrounds both stem 8 and part 21, fastening them together. The rear end of the member 13 is provided with a lug 15, extending upward therefrom and adapted to enter the depression 14 in the stem 8, to hold the member 13 in alignment and to act as a hinge between the parts 8 and 13.

The smoking pipe is inserted into the case by 30 forcing the head 22 downward, against the action of the rubber ring 17; inserting the stem of the pipe into the groove 11, until the base of the pipe bowl passes over the flanged head 22 of the lower member 13, and the top of the pipe bowl passes under the flange 10 and into the inverted cup 9 formed therefor, when the member 13 closes under the action of the elastic ring 17 and encloses the pipe completely within its structure, except that the sides of the pipe bowl are left exposed to enable the pipe to be firmly grasped by the user's fingers to remove it from the case 40 by the reversal of the above-described action.

It is, of course, understood that the particular size and shape of the case may be varied to accommodate the particular design of the pipe and that slight changes may be made in the 50 above described case without departing from the spirit of my invention, as outlined in the appended claims.

Having described my invention, what I claim and desire to secure by Letters Patent is:

55 1. A smoker's pipe case adapted to receive a

smoker's pipe having a stem and a bowl; comprising an upper member including a groove in its under side adapted to cover the stem of a pipe, and a head extending upward from one end of said upper member and having an inverted cup adapted to receive the top of the pipe bowl; an under member adapted to close the groove for the pipe stem, and having a flanged head extending upward from the end of said lower member and coaxial with said head of the upper member and adapted to enclose the lower end of the pipe bowl; and an elastic ring encircling the upper and lower members to hold them together.

2. A pipe case as set forth in claim 1, wherein the inverted cup of the head of the upper member, and the head of the under member are sep- 15

arated by a substantial distance, thereby permitting the pipe bowl to be grasped while the case is still closed.
